UNITED STATES PATENT OFFICE.

WILLIAM A. WEDNBINE, EDWARD LUSTENADER, AND ROBERT F. LUSTENADER, OF NEW YORK, N. Y.

OIL BURNER.

Application filed November 6, 1920. Serial No. 422,357.

To all whom it may concern:

Be it known that we, WILLIAM A. WEDNBINE, EDWARD LUSTENADER, and ROBERT F. LUSTENADER, citizens of the United States, 5 residing at New York, borough of Queens, in the county of Queens and State of New York, have invented a new and useful Oil Burner, of which the following is a specification.

10 This invention relates to oil burners; and especially to that class adapted to vaporize the oil and burn the same mixed with air; and the objects of our invention are: to provide for the vaporization of any kind of 15 burnable oil by the heating of the vaporizers with an impinging flame forming a part of the volume of flame used for other purposes in addition to other methods of heating the several vaporizers; to provide means to 20 place oil in the vaporizers at each end; to provide a number of vaporizers for the proper production of the vapor and the proper commingling of air therewith; and, to provide an air control for the vaporized 25 oil.

The invention is illustrated in the accompanying drawing, in which—

Fig. 1, is a plan view of an oil burner constructed in accordance with our invention;

Fig. 2, is a sectional view, illustrating a mode of application;

Fig. 3, is a plan view of a portion of a couple of vaporizers, showing a modified 35 form of construction; and,

Fig. 4, is a sectional view of the vaporizers shown in Figure 3.

In the drawing, like numerals of reference refer to the same parts in each of the 40 views.

In practice we provide an oil burner 5, preferably enclosed with a removable casing 6 so ready access can be had to the vaporizer for the purpose of cleaning, or for any 45 other purpose.

The burner 5 is preferably made up of a number of vaporizers, or vaporizing troughs 7, which are so constructed and mounted that a portion 8 projects over a portion of

the bottom 9, thereby lying within the zone 50 of the flame of the oil vaporized in the troughs. This is accomplished by tilting each trough so the side 8 is higher than the side 10; and air coming from the blower 11 will pass upward from beneath the 55 troughs, and will commingle and support combustion of the vaporized oil before the flame has ascended above the side 8, thereby heating the entire trough, or vaporizer by conduction, as will be understood. To further the mixture of the air and vaporized oil we bevel the edge of the side 10, as shown at 12. This makes a sharp edge 13 on each vaporizing trough over which the air must pass to commingle with the vapor, as will 60 be clear; and this sharp edge seems to work for a more intimate mixture of the air and vapor than would occur if there was any thickness of metal between the ascending air and the ascending vapor.

To further break up the air, we have provided the fillets 14 between the troughs. These fillets may be integral, as shown, or may be inserted pieces, as will be clear; but by providing obstructions of this kind at 75 intervals the air is divided, and currents are provided which seem to enter the vapor of the oil more thoroughly thereby producing better combustion. It will be noticed, too, that by providing the beveled edges 12, we 80 are able to mount the vaporizing troughs in close proximity thereby providing for a certain amount of heat for each vaporizing trough from the radiant heat transmitted by the next vaporizing trough, as will be clear. 85

In operation, air ascends from the blower 11, through the pipe 15 into the chamber 16, where it is divided and ascends between the various vaporizing troughs 7. The oil is admitted at each end of each vaporizing 90 trough through the respective valves 17 and 17', so that troughs of considerable length can be used, and the oil 18 will be evenly distributed in each trough, as the oil can have time to meet before being vaporized. 95 Thus, the vapor will arise throughout the entire length of each trough, as will be clear; and the air ascending from the blower will

thoroughly commingle with this vapor, as will be understood. The obstructions, or fillets 14 further assist in thoroughly commingling the vapor, and air, and the air 5 passing between the vaporizers will be heated thereby producing better combustion.

In practice the burner is preferably mounted in a separate receptacle at one side of a combustion chamber 19, so the burning 10 vapor and air will reach its greatest intensity of heat within this combustion chamber.

Oil is admitted to the troughs, and when evenly distributed in the troughs, is ignited. 15 The blower is then started, or the air is turned on through the valve 20, when a flame will soon develop that is substantially free from soot, and intense in its heating qualities. After the combustion has fully 20 started, the oil will be vaporized and will burn in a manner, as described above, to keep the several vaporizing troughs hot enough to continue to vaporize the oil, even although of a very heavy consistency and 25 the vaporizers will be kept below the melting point.

It will thus be seen that we have provided an oil burner that is cheap to manufacture, and efficient in use.

30 In Figures 3 and 4 we have shown a modified form of construction in which the troughs 7' are used without the fillets; but in this construction the troughs are tilted, as described above, so the higher side will 35 project over a portion of the bottom 9'. Thus, the burner 5' will act efficiently even with the fillets omitted.

We claim:

1. In an oil burner, a plurality of vaporizers spaced apart and means to pass air between them, each vaporizer having an open top whereby a trough is formed throughout its extent adapted to receive the oil being vaporized, said vaporizers being tilted 45 whereby each has a portion thereof projecting over the bottom of the trough against which the flame is adapted to beat thereby providing supplementary means for heating the vaporizer, for the purpose set forth.

50 2. In an oil burner, a plurality of vaporizers mounted in close proximity, each vaporizer having an open top whereby a trough is formed adapted to receive the oil being vaporized, the vapor being free to rise 55 throughout the length of each vaporizer, one side of each vaporizer having a portion thereof projecting over the bottom of the trough, and the other side having a comparatively sharp edge, and means to force air upward between the troughs.

3. In an oil burner, a plurality of vaporizers mounted in close proximity, each vaporizer having an open top whereby a trough is formed adapted to receive the oil being 65 vaporized, one side of each vaporizer hav-

ing a portion thereof projecting over the bottom of the trough, and the other side having a comparatively sharp edge, means to force air upward between said troughs, and means to divide the ascending currents of air between said troughs. 70

4. An oil burner comprising a plurality of vaporizers mounted in close proximity and joined together with fillets at a plurality of points, each vaporizer having an open top 75 whereby a trough is formed adapted to receive the oil being vaporized, one side of each vaporizer having a portion thereof projecting over the bottom of the trough, and the other side having a comparatively sharp 80 edge, means to force air upward between said trough, and means to regulate the flow of oil to said troughs.

5. In an oil burner, a vaporizer U-shaped in form having one side thereof projecting over a portion of the bottom of the trough, the other side having a beveled edge, and means to admit air to the vaporized oil along 85 said beveled edge prior to the ascension of the flame above said projecting portion 90 whereby the vaporizer is heated.

6. In an oil burner, a plurality of vaporizers, each U-shaped in form having one side of each projecting over a portion of the bottom of the trough, the other edge of each 95 vaporizer being beveled, and means to admit air to the vaporized oil along the beveled edge of each trough prior to the ascension of the flame above said projections whereby the vaporizers and air are heated, for the 100 purpose set forth.

7. In an oil burner, a casing having an open top, a plurality of vaporizers mounted in said open top, each vaporizer being U-shaped in form in cross section and mounted 105 in a tilted manner whereby one edge of each vaporizer is higher than the other—the lower edge being beveled, means to force air in a controlled manner between said vaporizers past said beveled edges into the vaporized oil prior to the ascension of the same above the higher edge of each vaporizer, and means to admit oil to each vaporizer at each end. 110

8. The herein described oil burner comprising a casing through which air may be passed, a plurality of vaporizers mounted in said casing, each vaporizer being U-shaped in form, and tilted whereby one edge is higher than the other, the lower edge being 115 beveled, means to force air past said vaporizers in a controlled manner, and means to admit oil to each end of each vaporizer.

9. An oil burner comprising a plurality of vaporizers spaced apart, each vaporizer comprising an open trough whereby vaporized fluid is free to rise therefrom throughout its length, each trough being tilted whereby one side thereof is higher than the other and projects in a vertical plane over a portion 120 125 130

of the bottom of the trough, and means to force air upward between the troughs.

10. An oil burner comprising a plurality of generating troughs forming vaporizers spaced apart, the vapor being free to rise from each trough throughout its length, each trough being tilted whereby one side thereof is higher than the other and projects in a vertical plane over a portion of the bottom

of the trough; and means to force air upward between said troughs—the lower edge of each trough being beveled whereby space is provided for the ascending air with the troughs mounted close together. 10

Dated 4th day of November, 1920.
